PORTABLE DERRICK

Herbert J. von Rosenberg, San Antonio, Tex.

Application May 5, 1941, Serial No. 391,973

6 Claims. (Cl. 212—142)

This invention relates to portable derricks.

An object of this invention is to provide a manually operable derrick for lifting or raising the desired articles or material, which is so constructed that the derrick structure may be rocked or tilted on the wheels thereof to thereby assist in elevating the articles.

Another object of this invention is to provide a portable derrick of this kind which is mounted on a pair of wheels, the axles of which may be swung within a radius of ninety degrees so that the wheels in one position thereof will prevent lengthwise shifting of the derrick structure.

A further object of this invention is to provide a derrick structure of this kind which is formed with an extensible base so that sufficient leverage may be provided in order to permit the ready shifting of the loaded derrick.

A further object of this invention is to provide a portable derrick including a pivoted boom and a pair of winches for raising or lowering the boom and raising or lowering articles relative to the boom.

A further object of this invention is to provide a portable derrick which may have the frame thereof made out of tubular material welded or otherwise fastened together so as to provide a relatively light weight and strong frame.

A further object of this invention is to provide a portable derrick which may be manually moved to a position straddling an opening or the like and which may be used with or without a boom to raise or lower articles or material and subsequently shift the articles or material to the desired location, or to initially shift the articles or material to the opening.

To the foregoing objects and to others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation of a portable derrick constructed according to an embodiment of this invention.

Figure 2 is a top plan of the derrick structure showing in dot and dash line the adjustable handle or frame structure,

Figure 3 is a sectional view taken on the line 3—3 of Figure 1.

Figure 4 is a sectional view taken on the line 4—4 of Figure 2.

Figure 5 is a sectional view taken on the line 5—5 of Figure 4.

Figure 6 is a sectional view taken on the line 6—6 of Figure 2.

Figure 7 is a bottom plan of the frame structure with the axles, boom and winch structure removed, and

Figure 8 is a sectional view taken on the line 8—8 of Figure 7.

Referring to the drawings, the numeral 15 designates generally a frame structure including a lower horizontal U-shaped frame 11 and a vertically disposed frame structure 12. The lower frame structure 11 comprises a pair of parallel side members 13 and 14, which are connected together at one end thereof by a connecting member 15 and arcuate members 16. In practice, the side members 13 and 14 and the end member 15 with the arcuate members 16 are formed from a single tubular member, which is bent in U shape. The vertical frame 12 includes a pair of vertically disposed tubular side members 17 and 18, which are connected together at their upper ends by a connecting member 19 having the opposite ends thereof downwardly bent, as at 20. In practice, the side members 17 and 18 with the connecting members 19 and 20 are formed as a single tubular member bent in U shape.

The lower end portions of the vertical frame members 17 and 18 are welded, as at 21 and 22, to the horizontal side members 13 and 14 respectively at a point slightly rearwardly from the forward ends of the horizontal lower side members 13 and 14. A pair of upwardly convergent bracing members 23 are secured as at 24 to the lower side members 13 and 14 adjacent the rear ends of these side members and the upper ends of the bracing members 23 are secured, as by welding 25 or the like, to the bight or connecting member 19 at a point inwardly from the opposite ends of the upper member 19.

A combined handle or leverage structure and lower frame extension generally designated as 26, is adjustably carried by the lower frame structure 11. The extensible frame structure 26 includes a pair of side rails or bars 27 and 28, which are connected together at one end thereof by a connecting member 29. The side members 27 and 28 and the end member 29 are formed as an integral tubular member. The side mem-

bers 27 and 28 are spaced apart substantially equal in distance to the spacing of the side members 13 and 14 so that the side members 27 and 28 may overlie the upper sides of the side frame members 13 and 14. The side frame member 13 is provided with a pair of U-shaped clamping members 30, which are spaced apart along the length of the side member 13 and which have the bight thereof welded or otherwise fixedly secured to the side frame member 13. The parallel legs of the clamp 30 extend above the side frame member 13 and a clamping bolt is extended through the parallel legs of the U clamp 30 and engages over the top of the side extensible frame 27.

The side frame member 14 is provided with a pair of longitudinally spaced apart U-shaped clamping members 32, which are similar in construction to the clamping members 30 and are welded or otherwise fixedly secured to the side frame member 14. A clamp tightening bolt 33 is carried by each of the clamping members 32 and engages over the top of the extensible frame member 28, so that tightening of the bolt 33 will tighten the parallel clamping legs of the clamp 33 and hold the side member 28 in longitudinally adjusted position with respect to the side member 13.

In order to provide a means whereby the frame structure 10 may be readily shifted over the ground or other plane surface, I have provided a pair of wheels 34, which are rotatably mounted on spindles or axles 35. The spindles 35 are each provided with a vertically disposed and right angular extension 36 and the extensions 36 are rotatable within the lower portions of the vertical side members 17 and 18. A collar 37 is fixed to each extension 36 adjacent the lower portion thereof against which the lower end of a side vertical frame member is adapted to engage. The collar 37 provides a means for limiting the upward extension of a spindle extension member 36 within the lower end of a side vertical frame member. The spindle 35 at a point inwardly from the outer end thereof may have fixed thereto a collar 38 against which the hub 39 of the wheel 34 is adapted to abut and an outer collar or washer 40 may engage against the outer end of the hub 39 and a cotter pin 41 extended through an opening 42 formed in the spindle 35 adjacent the outer end thereof. In this manner the wheel 34 is held against endwise movement, but is permitted free rotary movement on the spindle 35.

In the normal use of the frame structure 10 the spindles 35 will be disposed at right angles to the side frame members 13 and 14. A spindle locking pin 43 is adapted to be extended through a pair of diametrically opposed openings 44, which are formed in the lower end portions of the side frame members 17 and 18 and also through an opening 45 formed in the spindle extension 36. The side frame members 17 and 18 are also provided with a second pair of opposed openings 46, which are at right angles to the openings 44, so that if desired the spindles 35 may be swung to the dotted line positions shown in Figure 2 with the wheels 34 in alignment and at right angles to the side members 13 and 14. With the wheels 34 in the right angular positions shown in Figure 2, the frame structure 10 is prevented from longitudinal movement but may be tilted or rocked with the wheels 34 acting as fulcrums. The turning of the wheels to an aligned position also permits the lateral shift-

ing of the frame to permit proper positioning of the boom.

A boom structure generally designated as 47 is pivotally carried by the frame structure 10 and includes a pair of rearwardly divergent tubular frame members 48 and 49, which are formed with parallel rear end portions 50 and 51 respectively. The rear end portions 50 and 51 are secured to bearing sleeves 52 and 53 respectively, and the sleeves 52 and 53 are rockably mounted on a horizontally disposed connecting bar 54 extending between the vertical side members 17 and 18. The opposite ends of the connecting bar 54 have fixedly secured thereto sleeves 55 and 56, which are vertically adjustable on the side members 17 and 18 respectively. The side member 17 is provided with a plurality of vertically spaced apart openings 57, and a locking pin 58 is extended through the sleeve 55 and a selected pair of openings 57 so as to adjustably hold the sleeve 55 along the length of the side member 17. The side member 18 is provided with a plurality of vertically spaced apart openings 59 and a locking pin 60 is extended through the sleeve 56 and a selected pair of openings 59 so as to hold the sleeve 56 in vertically adjusted position.

The boom 47 also includes a centrally disposed tubular member 61, which is secured to the forward or convergent ends of the side members 48 and 49 as by welding or the like and preferably the tubular member 61 is secured as shown in Figure 2, to the side members 48 and 49 at a point rearwardly of the forward end of the tubular member 61 so that a substantial portion of this member 61 will be extended between and rearwardly from the convergent ends of the side members 48 and 49. The rear end of the tubular member 61 is welded to a transverse tubular member 62, which is welded or otherwise secured at the opposite ends thereof to the side members 48 and 49.

A boom extension 63 is engageable within the tubular member 61 and is adapted to extend forwardly of the forward end of the tubular member 61, as shown in Figure 2. A U-shaped clevis 64 is fixedly secured, as at 65, to the forward end of the extension 63 and a pulley or sheave 66 is rotatably mounted between the side arms of the clevis 64. An article or material elevating member 67 in the form of a rope or other flexible member is trained about the pulley or sheave 66 and is also trained through a sheave 68 which is swingably carried by an eye 69 mounted on the connecting member 19. A winch structure 70 is fixed to the vertical side rail 17 at a point upwardly from the lower end thereof, as by welding or the like, and the flexible elevating member 67 is wound about the drum 71 forming part of the winch structure. This winch structure may be of conventional construction and is here shown as a U-shaped frame 72 which may be welded or otherwise fixed to the inner side of the side members 17 and a crank 73 is connected with the drum 71 for manually turning the drum 71 to wind the flexible member 67 thereabout. It will, of course, be understood that if desired a power operated winch structure may be used in place of the manually operable winch structure 70.

In order to provide a means whereby the boom 57 may be manually elevated or lowered I have provided a boom operating winch structure generally designated as 74. The winch structure 74 is fixed as by fastening devices 75 to a horizon-

tally disposed plate 76, which is welded or otherwise fixed between the inclined bracing members 23 at a point intermediate the upper and lower ends of the bracing members 23. A boom elevating flexible member 77 is wound about the drum 78 of the winch structure 74 and is also trained through a swingable sheave 79 carried by an eye 80. The eye 80 is mounted on the horizontal connecting member 19 at one side of the eye 69. The boom elevating member 77 has one end thereof connected with an eye 81, which is fixed to the tubular member 64 adjacent the forward end thereof.

In the use and operation of this derrick structure the desired material or articles may be connected with the flexible member 67 and the boom 47 raised by means of the flexible member 77 to the desired position in order to elevate the article or material above the ground to the desired point. The derrick structure may then be shifted to the desired location and where the article being shifted is relatively heavy the lower frame extension 26 may be adjusted lengthwise to the desired degree by means of the clamping members 30 and 32 to give the desired leverage to the lower frame structure of which the extension 26 forms a part. After the derrick structure has been shifted to the desired location the material raising and lowering winch structure 70 may be operated to lower the articles or material to the desired point. During the lowering operation, if desired, the entire derrick structure may be tilted so as to lower the forward end of the boom 47.

In the event the articles which are being raised by means of the boom structure 47 are such as might shift the frame structure 10 rearwardly by rotation of the wheels 34, these wheels may be initially swung to an aligned position which is the position shown in dotted lines in Figure 2. During the initial raising of an article or material, the boom structure may, if desired, be lowered to the extent desired which may be at a downward and forward inclination and the two frame members 11 and 26 may then be at an upward inclination. After the article or materials have been attached to the elevating cable 67, the entire derrick structure may be tilted by lowering the two frame members 11 and 26. Where this tilting movement will not raise the articles or material to the desired degree the winch structure 70 may be operated to raise the articles or material relative to the boom and subsequently the boom elevating and lowering winch 74 may be operated to elevate the forward end of the boom 47.

This derrick structure is adapted to be constructed primarily out of tubular material, which is welded together so as to form a substantially light frame structure which can be readily shifted or moved from one point to another. The wheels 34 are spaced apart a sufficient distance so that in most instances these wheels can be disposed on opposite sides of a ditch or other opening. In the event the material which is being elevated is of such a weight that it might raise the rear end of the lower frame structure including the frame members 11 and 26, a weight or the like may be placed on the lower end of this horizontal frame structure and after the article or material has been raised to the desired degree the weight may be removed and the derrick structure shifted to the desired point with the material in an elevated position.

The derrick herein disclosed may also be with 75

the frame 12 in an initially horizontal position and the frame 11 in a vertical position, so that when the load is applied to the boom the entire structure may be tilted to raise the frame 12 and lift the article without operation of the boom. Furthermore, if desired a balancing load may be mounted on the frame 11 or the extension 26 to maintain the load in a substantially balanced position as it is moved to the desired point. In certain instances also it may be desirable to remove the extension 26 and also the boom 47.

What I claim is:

1. A portable derrick comprising a frame including right angularly disposed vertical and horizontal U-shaped frame members having the ends of the parallel legs thereof fixed together, a pair of bracing members fixed to said frame members, a pair of wheels, a right angle spindle for each wheel having one side thereof telescoping into the lower ends of said vertical frame members, and means engageable with said vertical frame members and said one side of a spindle for locking said spindles to thereby dispose said wheels in either parallel relation or in alignment, said frame being rockable about the axes of said wheels when the latter are in parallel relation.

2. A portable derrick comprising a frame including right angularly disposed vertical and horizontal U-shaped frame members having the ends of the parallel legs thereof fixed together, a pair of bracing members fixed to said frame members, a U-shaped extensible frame member having the parallel legs thereof overlying the parallel legs of said horizontal frame, clamping members carried by said horizontal frame for holding said extensible frame in adjusted position, a pair of wheels, a right angle spindle for each wheel having one side thereof telescoping into the lower ends of said vertical frame members, and means engageable with said vertical frame members and said one side of a spindle for locking said spindles to thereby dispose said wheels in either parallel relation or in alignment, the axes of said wheels when the latter are in parallel relation constituting the fulcrum about which said frame is rockable, and the contacting portions of said wheels with a plane surface when the wheels are in alignment constituting the fulcrum about which said frame is also rockable.

3. A portable derrick comprising a frame including right angularly disposed vertical and horizontal U-shaped frame members having the ends of the parallel legs thereof fixed together, a pair of bracing members fixed to said frame members, a pair of wheels, a right angle spindle for each wheel having one side thereof telescoping into the lower ends of said vertical frame members, means engageable with said vertical frame members and said one side of a spindle for locking said spindles to thereby dispose said wheels in either parallel relation or in alignment, a boom for said frame, and means extending between the parallel legs of said vertical frame member for pivotally mounting said boom on said vertical frame member, said latter means also constituting a brace for holding the legs of said vertical frame member against spreading.

4. A portable derrick comprising a frame including right angularly disposed vertical and horizontal U-shaped frame members having the ends of the parallel legs thereof fixed together, a pair of bracing members fixed to said frame

members, a pair of wheels, a right angle spindle for each wheel having one side thereof telescoping into the lower ends of said vertical frame member, means engageable with said vertical frame members and said one side of a spindle for locking said spindles to thereby dispose said wheels in either parallel relation or in alignment, a boom for said frame, a horizontally disposed pivot member for said boom, right angularly disposed sleeves carried by said pivot member loosely engaging the legs of said vertical frame member, and means holding said sleeves in vertically adjusted position, said pivot member also constituting means for holding the legs of said vertical frame member against spreading.

5. A portable derrick comprising a frame including a pair of right angularly disposed U-shaped frame members, a pair of wheels rotatably carried by said members, a boom, means pivotally mounting said boom on one of said frame members, said boom including a pair of outwardly convergent tubular members, a tubular socket fixed between the convergent ends of said tubular members and having an open outer end, an extension member engaging in said socket, a sheave carried by said extension member, said pivotal mounting means including a horizontal bar, a sleeve at each end of said bar

slidable on said one frame member, and means locking said sleeves in vertically adjusted position, said bar and said sleeves also holding said one frame member against spreading.

6. A portable derrick comprising a frame including a pair of right angularly disposed U-shaped frame members, a pair of wheels rotatably carried by said members, a boom, means pivotally mounting said boom on one of said frame members, said boom including a pair of outwardly convergent tubular members, a tubular socket fixed between the convergent ends of said tubular members and having an open outer end, an extension member engaging in said socket, a sheave carried by said extension member, said pivotal mounting means including a horizontal bar, a sleeve at each end of said bar slidable on said one frame member, means locking said sleeves in vertically adjusted position, said bar and said sleeves also holding said one frame member against spreading, a pair of winches carried by said frame, a flexible member wound about one winch and connected with said boom for elevating or lowering the latter, and a flexible member wound about the other winch and trained through said sheave for elevating or lowering an article relative to said boom.

HERBERT J. VON ROSENBERG.
